US0D1043722S

(12) **United States Design Patent** (10) Patent No.: **US D1,043,722 S**
(45) Date of Patent: ** Sep. 24, 2024

(54) **DISPLAY SCREEN OR PORTION THEREOF WITH GRAPHICAL USER INTERFACE**

(71) Applicant: **Fiduciary Benchmarks Insights, LLC**, Tigard, OR (US)

(72) Inventors: **Pavel Kosobutskiy**, Minsk (BY); **Anton Kachan**, Lida (BY); **Dzmitry Kazakou**, Mogilev (BY)

(73) Assignee: **Fiduciary Benchmarks Insights, LLC**, Tigard, OR (US)

(**) Term: **15 Years**

(21) Appl. No.: **29/866,859**

(22) Filed: **Sep. 29, 2022**

(51) LOC (14) Cl. **14-04**

(52) U.S. Cl.

USPC **D14/486**

(58) **Field of Classification Search**

USPC D14/485-495

(57) **CLAIM**

The ornamental design for a display screen or portion thereof with graphical user interface, as shown and described.

DESCRIPTION

The FIGURE is a front view of a display screen or portion thereof with graphical user interface.

The outermost broken lines showing the display screen or portion thereof form no part of the claimed design. The other broken lines showing portions of the graphical user interface form no part of the claimed design. Dotted portions bounded by solid lines showing portions of the graphical user interface form no part of the claimed design.

1 Claim, 1 Drawing Sheet
